UNITED STATES PATENT OFFICE

JOHN W. STEPHENSON, OF TOLEDO, OHIO, ASSIGNOR TO THE NATIONAL
MALLEABLE CASTINGS COMPANY, OF CLEVELAND, OHIO.

LID FOR CAR-AXLE BOXES.

SPECIFICATION forming part of Letters Patent No. 644,036, dated February 20, 1900.

Application filed December 1, 1899. Serial No. 738,770. (No model.)

To all whom it may concern:

Be it known that I, JOHN W. STEPHENSON, of No. 520 Euclid avenue, Toledo, county of Lucas, and State of Ohio, have invented a new and useful Improvement in Lids for Car-Axle Boxes, of which the following is a full, clear, and exact description, reference being had to the accompanying drawings, forming part of this specification, in which—

10 Figure 1 is a vertical longitudinal section on the line I I of Fig. 2 of my improved lid for car-axle boxes. Fig. 2 is a front elevation. Fig. 3 is a horizontal section on the line III III of Fig. 1. Fig. 4 is a cross-section on the line IV IV of Fig. 1. Fig. 5 is similar to Fig. 1, showing a modified form of lid, being a vertical longitudinal section on the line V V of Fig. 7. Fig. 6 is a side elevation of the same. Fig. 7 is a horizontal section on 20 the line VII VII of Fig. 5, and Fig. 8 is a cross-section on the line VIII VIII of Fig. 5.

The object of my invention is to provide a lid of simple and efficient construction which will fit neatly to its seat on the face of the 25 car-axle box even when the hinge-lug of the box is out of parallel with the edge of the box.

In Figs. 1 and 2 of the drawings, 2 represents the car-axle box, having the usual hinge-lug 3. 4 is the pintle or hinge-pin, and 5 is a 30 closing-arm having hinge-lugs 5' 5'', through which the pin passes. 6 is the axle-box lid, which is connected to the closing-arm 5 by a stud 7 on the arm, whose head fits loosely in an open socket 8 on the face of the lid. The 35 lid is also connected loosely at the hinge portion of the box to the closing-arm 5 or to the hinge-pin—preferably to the hinge-pin—by lugs 9, through which the pin passes and which are of larger diameter than the pin, so 40 as to permit some loose or free motion of the lid. The spring 10 may be of usual construction and bears at one end upon the closing-arm and at the other end against the face of the lug 3, so that it exerts upon the closing-arm a tension pressing it toward the face of the box. When the parts are assembled as 45 above described, the lid will be held against the box by the closing-arm, and as the lid is connected loosely both with the closing-arm

and the hinge-pin it can accommodate itself 50 to its seat on the box even when the hinge-pin by reason of malformation or warping of the hinge-lugs is not in proper alinement.

The construction is simple and strong, and the device as a whole is very efficient because 55 of the double connection of the lid—namely, the loose connection of the body portion of the lid with the closing-arm and its loose connection at the hinge portion—for these two connections not only afford sufficient flexibility to the lid to cause it to seat properly, but at the same time they hold it sufficiently well to make it steady and to prevent it from wobbling.

In Figs. 5, 6, 7, and 8 I show a modification 65 of my invention, in which, instead of connecting the closing-arm to the body of the lid by a stud and socket, as above described, the arm may be formed with eyes 7', which engage hooks 8' on the lid, or the eyes may be on the 70 lid and the hooks on the arm. I also illustrate in these figures a modified loose connection of the lid at its hinge end with the closing-arm. In this case I form lips 11 on the margin of the lid, which fit over the hinge-lugs of the closing-arm, being bent inwardly 75 for that purpose. This construction affords, though in a different form, the same kind of loose connection as described above with reference to Figs. 1 and 2.

In order to make the lid dust-proof and otherwise to increase its efficiency, I provide it with a lip 12 at its upper margin, which fits across the top edge of the box, and I also prefer to form lips 13 along the lateral edges 85 of the lid, which engage the outer edge of the box. I also form on the inner side of the lid a lip 14, which when the lid is closed overhangs the lower edge of the box-opening and acts as a deflector or shed, causing the oil 90 which accumulates on the lid to run down into the box instead of exuding at the joint between the box and lid. I also provide projections 15, which extend on the lid upwardly from the lip 14 and serve to prevent the oil 95 from spreading sidewise and running out at the corners of the box; and by preference these projections are made angular in form.

The lips and projections named in this paragraph may be applied to lids of other construction.

Modifications of my invention will be suggested to those skilled in the art; since

What I claim is—

1. The combination of an axle-box, a lid, and a spring-actuated closing-arm hinged to the box, connected loosely with the body of the lid and adapted to force the same against its seat, said lid being also loosely connected with one of the said parts at the hinge portion; substantially as described.
2. The combination with the lid, of a spring-actuated closing-arm, and a stud on the arm fitting an open socket on the lid; substantially as described.
3. The combination of an axle-box, a lid, and a spring-actuated closing-arm hinged to the box, connected loosely with the body of the lid and adapted to force the same against

its seat, said lid having lugs fitting loosely at the hinge-pin; substantially as described.

4. An axle-box lid have an oil-shedding lip on its inner surface adapted to lie over the edge of the box and having upward projections to prevent spreading of the oil; substantially as described.

5. An axle-box lid having on its inner surface projections adapted to prevent lateral spreading of the oil; substantially as described.

6. An axle-box lid having on its inner surface angular projections adapted to prevent lateral spreading of the oil; substantially as described.

In testimony whereof I have hereunto set my hand.

JOHN W. STEPHENSON.
